Des. 211,997

Patented Aug. 20, 1968

211,997

TAPE RECORDER OR SIMILAR ARTICLE

Tetsujiro Hasegawa, 19-4 Nakacho, 2-chome,
Meguro-ku, Tokyo, Japan

Filed July 26, 1967, Ser. No. 8,005

Term of patent 14 years

(Cl. D26—14)

FIG. 1

FIG. 4

FIG. 3

FIG. 2

FIGURE 1 is a front perspective view of a tape recorder or similar article showing my new design; the tape cartridge is shown in broken lines for purposes of illustration only;

FIGURE 2 is perspective view from the rear and right side;

FIGURE 3 is right side view; and

FIGURE 4 is bottom plan view.

The dominant features of my design reside in the portions shown in full lines.

I claim:

The ornamental design for a tape recorder or similar article, substantially as shown and described.
